US00D743461S

(12) **United States Design Patent**
Libasci

(10) **Patent No.:** **US D743,461 S**
(45) **Date of Patent:** **** Nov. 17, 2015**

(54) **PARTICLE SIZE CLASSIFICATION DEVICE
FOR FIELD USE**

(71) Applicant: **Linda Libasci**, College Station, TX (US)

(72) Inventor: **Linda Libasci**, College Station, TX (US)

(**) Term: **14 Years**

(21) Appl. No.: **29/498,415**

(22) Filed: **Aug. 4, 2014**

(51) LOC (10) Cl. **15-09**

(52) U.S. Cl.

USPC **D15/147**

(58) **Field of Classification Search**

USPC D15/147

See application file for complete search history.
